UNITED STATES PATENT OFFICE.

GEORGE C. BRAINARD, OF YOUNGSTOWN, OHIO, ASSIGNOR TO THE GENERAL FIRE-PROOFING COMPANY, OF YOUNGSTOWN, OHIO, A CORPORATION OF OHIO.

METAL DESK CONSTRUCTION.

Application filed November 9, 1925. Serial No. 67,896.

This invention relates to a system of construction for making metal desks involving the production, in an expeditious and practical manner, of a desk structure possessing 5 exceptional strength and durability while at the same time having interchangeable parts or members which greatly facilitate the manufacture of the desks in different sizes and types.

10 One of the desirable objects of the invention is to provide a construction which permits of the standardization of many of the units comprising the desk. This enables the manufacturer to carry such units in stock to 15 be assembled according to predetermined specifications or plans to provide desks of various sizes and types, for example desks of standard office type having one or more drawer units, typewriter desks, or combination office and typewriter desks and the like. In that connection the invention contemplates a system of fabrication which enables the various units to be assembled with great facility, thereby not only enhancing production, but at the same time adapting the desks, if conditions make it desirable, to be 20 shipped in knock-down condition to be set up at the destination.

Another object of the invention is to 30 provide a desk construction having a novel top which constitutes the base upon which the rest of the structure is fabricated and assembled. That is to say, it is proposed to provide a flat sheet metal top which is adequately 35 braced to give rigidity and solidarity, and which constitutes the main anchoring base or carrier which can be laid in an inverted position and is adapted to have the entire desk structure built-up thereon and locked 40 thereto while remaining in that position.

A further object of the invention is to 45 provide a metal desk construction having the general features and characteristics above pointed out and wherein the drawer pedestals cooperate with the legs and with the reinforcement of the table top to act as a stiffening brace thereby materially strengthening the entire structure and adding to its stability.

50 Another general object of the invention is to provide a system of desk construction wherein all of the parts or units depend upon the table top for their rigid support and are so arranged and related that if one part or 55 unit should happen to be damaged in service

that part or unit can be readily removed by the use of a screw-driver and a small wrench and can be replaced by a corresponding part or unit. Also the different parts or units of this desk structure can be painted or finished according to various color schemes without digressing from the design or method of manufacture, the result being that the invention permits of manufacturing a large assortment of desks and tables under 60 economical and facile conditions thereby widening the range of manufacture of these articles without increasing overhead or fabricating costs.

65 The essential features of the invention involving the special objects above indicated are necessarily susceptible of a wide range of structural modification without departing from the spirit or scope of the invention, but a preferred and practical embodiment of the 70 invention is shown in the accompanying drawings, in which:

75 Figure 1 is a perspective view of one type of desk that may be constructed in accordance with the present system of fabrica- 80

85 Figure 2 is a bottom plan view of the stiffened and reinforced table top shown in the inverted position in which it is placed on a stand or work horses to provide the base 90 upon which the rest of the desk structure is fabricated or built-up, the inverted fabricating position of the parts being also shown in the succeeding Figures 3, 4, 5, 7, 8, 9 and 10.

95 Figure 3 is a view similar to Figure 2 illustrating the fabricating steps of installing the legs, end panels and draw units or pedestals.

Figure 4 is a vertical sectional view taken 105 on the line 4—4 of Fig. 3.

Figure 5 is an enlarged detail bottom perspective view of one of the corners of the top construction, a portion thereof being broken away to show the manner of inserting and 100 fastening a leg to the inside flange of the apron or frame carried by the top.

Figure 6 is a detail perspective view of one 110 of the hollow leg members.

Figure 7 is a detail perspective view illustrating the manner of applying the end panels to the legs and top.

Figure 8 is a perspective view similar to Figure 7 showing the additional step in the system which involves the connection of the 110

drawer pedestal with the top and leg members.

Figure 9 is a vertical cross sectional view taken on the line 9-9 of Figure 8.

5. Figure 10 is a vertical cross-sectional view taken on the line 10-10 of Figure 8, the line of section being at right angles to the line of section on which Figure 9 is taken.

Figure 11 is a detail vertical cross sectional view of the edge construction of the table.

Similar reference characters designate corresponding parts throughout the several figures of the drawings.

As above pointed out the present system of desk construction involves the making of different combinations and arrangements of legs, drawer pedestals and panels and to render them interchangeable according to the type of desk or table to be built, but in all embodiments of the invention the different interchangeable stock parts and units are adapted to be assembled and fastened to each other and to the table top while the latter is in inverted position on a work bench or horses and constitutes a bottom or foundation on and from which proceeds the work of fabricating.

30 The primary feature in the new desk construction as well as in the system of fabricating the same is the table top designated generally by the reference letter T. This table top is of special construction to provide adequate stiffening and reinforcement not only to its edge portions, but also 35 throughout its entire extent both longitudinally and transversely. That is accomplished by constructing the table top of a flat metal sheet indicated by the numeral 1, the same being of the desired or required 40 size and having rigidly united thereto an edge framing designated generally by the reference letter A. This edge framing surrounds the entire top sheet just inside of the bottom edge portion thereof and, preferably 45 is of a tubular or hollow form consisting of an attaching base 2 and the inside and outside apron pieces 3 and 4 respectively, which apron pieces are in substantially parallel 50 relation and are respectively provided with the inturned supporting flanges 5 and 6 respectively. It is preferable in this part of the construction to rigidly unite the edge framing A to the bottom edge portion of the top sheet 1 by a suitable welding operation 55 as by the spot welding 7 plainly indicated in Fig. 2 of the drawings. Also in constructing the edge framing A it is preferable to provide an offset 8 in its attaching base 2 forming an edge pocket 9 which extends entirely around the bottom edge of the table 60 top for the purpose of receiving a bead strip B as will hereinafter more fully appear.

65 It will be further observed, particularly from Figs. 4, 5 and 10 of the drawings that the inside flanged apron piece 3 of the hollow

edge framing A is of a greater depth than the flanged outside apron piece 4 corresponding to the depth or width of the flanged stiffening members S which are located in and on the intermediate part of the top sheet inside of the boundaries of the said edge framing. Preferably a plurality of the stiffening members S are employed and these members consist of Z-plates or bars disposed longitudinally of the top and having their top flanges 10 welded or otherwise secured to the top sheet while their horizontal bottom flanges 11 provide attaching or anchoring means for certain parts of the structures built-up thereon.

Before the assembly begins of the legs, the drawer pedestals and the panels, the side and end sections of the edge framing A are bridge-welded together at the ends as indicated by the hatching 12 particularly in Figs. 2 and 8 of the drawings, thereby making an integral rectangular frame surrounding the edge of the table having the effect of very substantially stiffening and strengthening the edge portion of the table while at the same time providing an attaching base for the legs, panels and other parts of the structure herein referred to and by reason of utilizing a plurality of Z-plates or equivalent stiffening members S throughout the mid-section of the table-top or top sheet 1. These stiffening members contribute to the strength and stiffness of the table top, having the effect of resisting any load or bending strains which may be imposed on the table top when in use and at the same time presenting through its attaching flanges 11 points of attachment to which may be secured the drawer pedestals or units. The table top structure as thus completed constitutes, as said before, the main base upon which the rest of the structure is built-up, while the said base is supported in a flat horizontal position on a low work-bench or upon work-horses which will enable the workman to have ready access to all parts of the structure as he fabricates the same.

The leg members L shown in Figure 6 are preferably of tubular formation and one end L' thereof is adapted to receive a novel foot construction F, the same forming the subject of the application of J. A. Fitch, Serial No. 732,468, while the opposite end L² is cut away to provide the attaching ends 13 which are provided with fastening receiving openings 13^a adapted to register with similar fastening receiving openings in the inner apron piece 3 thereby to receive the bolts 14 or the equivalent fastenings.

As will be observed from Figure 5, for example, the said attaching ends 13 fit against the corner formed by the inner apron piece 3 while the cut away portion of the leg rests upon the inturned flanges 5 thereof. The inside faces of the leg members are

provided with the openings 15 and 16, the former adapted to register with similar openings in the flanges 17 of the end panels E to permit of fastenings 18 connecting the end panels E with the leg members as shown in Fig. 7. When the leg members and the panels E are assembled as shown in Fig. 7 it will be apparent that the same are adequately braced by the gusset-like plate or 10 end panel, thereby imparting a bracing effect to the leg members across or transversely of the table top.

After the end panels E have been connected to the legs as above described the 15 drawer pedestal P may be placed in position. As will be observed from Figures 8, 9 and 10 for example, the said drawer pedestals P preferably comprise a box-like casing whose walls are rigidly connected and braced by 20 the corner or fillet braces 19 (Fig. 9). The side walls 20 of the pedestals which are adjacent to the leg members are provided with fastening receiving openings for registering with the openings 16 in the leg members, 25 thereby permitting of utilizing the fastenings 21 (Fig. 10) for connecting the inside walls of the panels with the legs, thereby further bracing the legs and adding to the rigidity of the structure. The top edges of 30 the side walls of the pedestal casing are provided with the flanges 22 having openings for registering with openings 22^a in the flanges 11 of the Z-shaped stiffening bars S to receive the fastenings 23, thereby connecting 35 the top of the pedestal with each one of the stiffening bars, and further increasing the rigidity and stability of the structure. In connection with the flanged stiffening plates or bars S it will be observed that the 40 bottom attaching flanges 11 thereof are punched or drilled with an extra number of holes or openings 22^a to adapt the same for having fastened thereto different sized pedestals, thus rendering a single table top 45 structure available for use with different types and sizes of drawer pedestals.

When the pedestals P are secured at the upper edges thereof to the stiffening bars S, and also to the leg members L it will be 50 apparent that the pedestal itself will greatly strengthen and stiffen the leg connection with the table top. As may be observed from Figure 1, the pedestals P in the type of desk shown may be connected at the rear 55 by a rear panel R which is a flanged member similar to the end panels E and is connected to the inside rear edges of the casings which form the pedestals by suitable fastenings, or other securing means.

60 The inside walls of the pedestal members may be provided with drawer guides G and drawer guide carriers G' as shown in Figure 10. Also the edges of the walls of the pedestal members at the open side of the pedestal 65 may be provided with an ornamental

channel shaped wall 24 as shown in Figures 1, 8 and 10.

When the structure has been fabricated up to the point described the same may be turned to its right-side up position shown in 70 Figure 1 and completed with such fittings and finishing touches that may be necessary in the process of putting out the desk or table.

In connection with the finished product it 75 will be observed by reference to Figure 11 that the upper face of the sheet metal top 1 is provided with a linoleum or equivalent covering C the outer edge of which is engaged by the angular bead strip B which 80 extends into the pocket 9. This bead strip is held in the pocket by the combined locking and finishing apron A² whose locking flange 25 engages with bead strip B to hold 85 it in the pocket 9 while the flange member 26 springs behind the edge of the flange 6 of the apron A thereby to hold the outer apron A in position. This edge construction is not claimed herein as it is described and 90 claimed in detail in the application of Fitch and Brainard Serial No. 703,185, filed March 31, 1923.

From the foregoing it will be apparent that the leg members L and pedestals P may 95 be made in accordance with predetermined specifications and when a desk of a particular type is to be made the top T is fabricated to meet the requirements, and the leg and pedestal members assembled thereon and secured in position. The assembling and 100 locking of the various units in position is preferably accomplished by the use of fastenings such as small screw bolts although it will of course be understood that any desired fastening means may be employed. However, with the construction and design of the parts shown in the drawings it will be apparent that the desks may be made with great 105 facility, and when shipped in a knock-down condition can readily be assembled by unskilled persons with no difficulty.

Furthermore, the placing of the end panels and the pedestals in the manner shown greatly braces and strengthens the entire 115 structure.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:—

1. A metal desk construction comprising a top sheet having at its underside reinforcing elements throughout its length, leg members located at the corners of the structure and each fastened to a reinforcement, and 130

a box-like drawer pedestal unit fastened to each end pair of legs and also to the longitudinal reinforcement for the top sheet thereby forming a rigid gusset bracing between the leg members and the reinforced top structure.

2. A metal desk construction comprising a top sheet having a reinforcing framing surrounding the bottom edge portion thereof, and other reinforcing members inside of said framing, leg members fastened to said framing at the corners thereof and drawer pedestal units fastened to said leg members and also to the framing and the other reinforcing members.

3. A metal desk construction comprising a top sheet having flanged reinforcing members rigid with the underside thereof, leg members fastened to said flanged reinforcing members, and drawer pedestal units fastened to said reinforcing members and also to said leg members.

4. A metal desk construction comprising a top sheet, a reinforcing flanged edge framing rigidly united with the bottom edge portion of the top sheet and including outer and inner apron pieces, leg members fastened to the inner apron pieces of said edge framing at the corners thereof, and drawer pedestal units fastened to said leg members and also to said inner apron piece of the edge framing.

5. A metal desk construction comprising a top sheet, an edge framing rigidly united with the top sheet at the bottom edge portion thereof and including outer and inner apron pieces, flanged stiffening members rigidly united to the underside of the top sheet and extending longitudinally thereof inside of the edge framing, leg members fastened to the inner apron piece of the edge framing at the corners thereof and drawer pedestal units fastened to the leg members and also to the inner apron pieces and to the flanged stiffening members.

6. A metal desk construction comprising a reinforced top structure carrying a rectangular frame at its under side adjacent its edge, leg members fitted to the corners of said rectangular frame, and drawer pedestal units secured at their upper edges to said frame and also connected at their sides with the leg members.

7. A metal desk construction comprising a top structure including a frame carried by the underside of the top adjacent the edge thereof, tubular leg members secured to the corners of said frame, stiffening members arranged within the frame and secured to the top structure, and drawer pedestal units secured at their upper edges to said stiffen-

ing members and also secured at their sides to the leg members.

8. A metal desk construction comprising a top structure including a double apron secured to the top structure adjacent the edges thereof and forming a rigid rectangular bracing frame, a plurality of longitudinally disposed stiffening members secured to the top structure within the frame, leg members secured to the apron, and drawer pedestal casings secured to the stiffening members and to the legs.

9. A metal desk construction comprising a top structure including an inner apron secured to the top structure adjacent the edges thereof and forming a rigid rectangular frame, longitudinally disposed flanged stiffening bars arranged lengthwise of the top structure and having certain of their flanges secured thereto, leg members secured to the corners of said apron, and drawer pedestal casings secured to the exposed flanges of the stiffening bars and also secured to the insides of the leg members.

10. A metal desk construction comprising a top structure including an apron secured to the top structure adjacent the edges thereof and forming a rigid rectangular frame, leg members secured to the corners of said rectangular frame, flanged end panels secured to opposite faces of the leg members, and drawer pedestal casings secured to the apron top structure and also to the leg members.

11. A metal desk construction comprising a sheet metal top having stiffening and reinforcing flanged members secured thereto, tubular metallic leg members secured to the reinforcement at the corners of the top structure, and hollow metallic drawer pedestal casings secured to the leg members and also to said reinforcement.

12. A fabricated desk construction comprising a top structure having edge and central reinforcement, vertical leg members attached to the edge reinforcement, and transversely disposed drawer pedestal casings fastened to the central reinforcement and also to the vertical leg members.

13. A fabricated desk construction comprising a sheet metal top member, angular metallic edge reinforcement forming a frame adjacent the edges of the top member, a plurality of straight reinforcing and stiffening members fitted to the metal top member within the frame, and drawer pedestal casings fastened to the reinforcement of the top structure and also to the leg members.

In testimony whereof I hereunto affix my signature.

GEORGE C. BRAINARD.
